UNITED STATES PATENT OFFICE

JOHN T. SCULLY, OF NEW YORK, N. Y.

VANITY-CASE COMPACT

Application filed December 9, 1927. Serial No. 238,855.

This invention relates to improvements in vanity case compacts and has especial reference to vanity case compacts which contain a mirror section foldable upon a powder container section, an object being to provide a puff which is housed removably in the compact and which has a handle.

Another object of the invention is the provision of a vanity case compact which has a handle thereon.

A further object of the invention is the provision of means in a handle of a powder daub which permits the puff to accommodate itself to the decrease in the height of the powder.

A further object of the invention is the provision of a vanity case compact which in addition to the above and other objects and advantages has simplicity and durability of construction and low cost of manufacture.

With the above and other objects in view, the invention further includes the following novel features and details of construction, to be hereinafter more fully described, illustrated in the accompanying drawings and pointed out in the appended claims.

In the drawings:

Figure 1 is a side elevation of the invention.

Figure 2 is a side elevation of the invention with parts broken away.

Figure 3 is a top elevation of the invention.

Figure 4 is a top view of parts of the invention.

Figure 5 is a front view of sections of the invention.

Figure 6 is a top elevation of a modification of a part of the invention.

Figure 7 is a sectional view along the line 7—7 of Figure 6.

Figure 8 is a top view with parts open of the invention.

Figure 9 is a side view of a modification of parts in Figure 8.

Figure 10 is an end view of Figure 8 with the lid closed and parts broken away.

It has been my observation in regarding the feminine sex while they apply talcum powder to the face that the puff which ac-

companies the powder in so called "compacts"—a small device, carried in the handbag, having a mirror, powder, a puff and means for opening a lid—is grasped in the fingers while applying the powder and as a result of having so much of the hand between the face and the small mirror even distribution or conscious uneven distribution of the powder is not so readily effected. Relatively speaking the hand is large while the puff and mirror are small. Consequently, in my present invention, I provide means to more efficiently and gracefully apply powder to the face in combination with a mirror, and these means are provided in a compact body easily and readily carried in a purse or other handbag.

Referring to the drawings in detail wherein like characters of reference denote corresponding parts, the reference character 1 indicates the lower portion of my compact which is of round shape and adapted to contain face powder, and the reference number 2 indicates the upper portion of the "compact," also round in shape. A mirror 9 is secured to the inner side of the top wall of 2 and cemented thereto. A hinge 3 connects the lower portion 1 to the upper portion 2. On the lower portion 1, as at 14 is secured a handle 4 which preferably has a ball shaped end 6^a. A catch projection 7 on the upper portion 2 is adapted to yieldably fit over a projection provided in the lower portion 1 to hold both portions yieldingly together. A powder puff 11 of lamb's wool or other suitable material is secured at 12 to a handle 5, having a ball shaped end preferably. The puff rests in the lower portion 1 above the powder 10 and the handle 5 projects outwardly of the portions 1 and 2. An angle 15 is provided in the handle 5 to permit the puff to be rubbed against the powder without the wall of 1 interfering with the handle 5. To permit the upper portion 2 of the compact to be closed over the handle 5, an opening 13 is provided in 2. This opening 13 rests upon the handle 5 beyond the angle 15 in the handle 5, as shown in Figures 1 and 2. The handles 4 and 5 are preferably provided with ball shaped ends 6 and 6^a because I prefer

to space part of the handles apart in order that the handles may be employed as levers to force the compact open, and, inasmuch as I prefer the top of the opening 13 to rest on the handle 5 when 1 and 2 are closed, the ends 6 and 6^a will serve to maintain a space between part of the handles so they may be easily grasped with the fingers for opening.

When, then, the compact is opened for use, 10 the user may hold the handle 4 in one hand. This handle 4, of course, will hold the portions 1 and 2 in position as shown in Figure 4, the portion 2 being foldable upwards on the hinge 3. The handle 5 of the puff 11 may 15 be grasped with the other hand, and by virtue of the angle 15 the puff may be swung through an arc in the powder containing portion 1, and then applied to the face.

In the above figures the puff 11 has been 20 shown of a round form and of soft yielding material.

In Figure 6 I show a rear view of a puff 11 having a changeable covering 16 covering the face of 11 and terminating at the rear in 25 the line 19. Elastic strips 17 and 17^a hold the covering in place.

Figures 8 and 10 illustrate a modification 30 in the shape of the puff and show soft material 16^a cemented to the face of the puff 11^a. In Figure 10 I illustrate the puff 11^a of Figures 8 and 10 having a handle 5^a of cylindrical shape to removably house a lipstick 5^c carried in a ferrule 5^b with a shoulder joint 23.

35 The invention is susceptible of various changes in its form, proportions and minor details of construction and the right is herein reserved to make such changes as properly fall within the scope of the appended claims.

40 Having described the invention, what I claim is:—

1. A vanity box comprising a powder receiving section, a lid section hingeably mounted to said powder receiving section, a mirror in said lid section, a powder daub housable within said powder section, and a handle for the daub, said handle projecting outwards beyond the walls of said powder receiving section and said lid section.

45 2. A vanity box comprising a powder receiving section, a handle on said powder receiving section, a lid section hingeably mounted to said powder section, a mirror in said lid section, a powder daub housable within said powder section and a handle for said daub, said handle projecting outwards beyond the walls of said powder receiving section and said lid section.

50 3. In a vanity box compact comprising a powder containing portion and a mirror holding portion, a handle projecting from the powder containing portion, a powder daub housed in said powder containing portion and a handle for said daub, said handle 55 projecting outwards beyond the said powder

containing portion and the said mirror holding portion.

4. In combination, a box adapted to contain face powder, a mirror held by a lid for said box, means on said box engaging means on said lid to yieldably hold said lid in closed position, powder applying means in said box, said powder applying means secured to a handle one end of which extends outside of said box through an aperture provided for that purpose.

5. In a vanity box compact comprising a powder containing portion and a mirror holding portion and having housed therein, a powder puff with a handle thereto, said handle of said powder puff having means therein to house the end of a cosmetic stick.

6. A vanity box comprising a powder containing portion and a mirror holding portion, said box housing having therein a powder puff with a handle thereto, said handle of said powder puff projecting outwards beyond said powder containing portion, and means included in said handle to house the end of a cosmetic stick.

7. In a face powder receiving compact having hingeably mounted thereto a lid section, a powder puff mounted between said compact and lid and having a handle thereto, said handle projecting outwards beyond the end wall of said face powder receiving compact.

In testimony whereof I affix my signature.

JOHN T. SCULLY.
